Charles Fair ATTYS.

UNITED STATES PATENT OFFICE.

OLIVER B. WOODROW, OF NEWTON, IOWA.

RELEASING DEVICE FOR WRINGERS.

Application filed July 8, 1919. Serial No. 309,404.

To all whom it may concern:

Be it known that I, OLIVER B. WOODROW, a citizen of the United States, and a resident of Newton, in the county of Jasper and State of Iowa, have invented a certain new and useful Releasing Device for Wringer, of which the following is a specification.

The object of my invention is to provide a releasing device for wringers, of simple, durable and inexpensive construction.

More particularly it is my object to provide the combination of a wringer of the type having pressure devices for imposing tension on the rolls, with means for operating the wringer including a reverse gear mechanism, and to provide a device for instantaneously releasing the tension on the wringer rolls, said device being adapted when operated to automatically throw the reverse gear mechanism into neutral position.

A further object is to provide in connection with the wringer a bar arranged to hold the wringer rolls under tension, and to provide a locking device for holding the parts in position for maintaining such tension, said parts being connected with a wringer operating mechanism whereby the movement of the parts, on the release of the tension, will operate a reverse gear mechanism for moving it to neutral position.

With these and other objects in view my invention consists in the construction, arrangement and combination of the various parts of the device, whereby the objects contemplated are attained, as hereinafter more fully set forth, pointed out in my claims and illustrated in the accompanying drawings, in which:

Figure 1 shows a front elevation of a device embodying my invention.

Figure 2 shows an end elevation of the same, the reverse gear mechanism being shown in vertical section.

Figure 3 shows a detail view of part of the mechanism.

Figure 4 shows a top or plan view of part of the reverse gear operating mechanism.

Figure 5 shows a vertical, sectional view taken on the line 5—5 of Figure 4.

Figure 6 shows a side elevation of the mechanism shown in Figure 4; and

Figure 7 shows an end elevation of the same.

Figure 8 is a detail, sectional view show-

ing the manner in which the wringer rolls are driven from the power shafts.

The wringer operating means including the reverse gear mechanism of my present device is similar in construction to that disclosed in my prior application No. 231,610 filed April 30, 1918.

In the drawings herewith which illustrate my invention I have used the reference numeral 10 to indicate generally a supporting bracket having the laterally extending arm 10^a. The bracket 10 and the arm 10^a thereon support a wringer having the upright end members 11 and the wringer rolls 12 and 13 mounted on shafts 14 and 15 which extend through the upright end members 11.

Formed on the bracket 10 is a journal 17 for an upright shaft 18. The journal 17 is supported above a sleeve or other support 17^a to permit the bracket and the wringer supported thereon to swing around the shaft 18. Mounted on one end of the wringer is a two-part gear casing 19, which receives a reverse gear mechanism at the upper end of the shaft 18, shown clearly in Figure 2.

Rotatably but non-slidably mounted on the shaft 18 within the gear casing 19 are opposite bevelled gears 20 and 21 which mesh with a gear 22 on the shaft 15 of the lower wringer roll.

On the adjacent portions of the gears 20 and 21 are clutch members 23.

Slidably but non-rotatably mounted on the shaft 18 between the gears 20 and 21 is a double clutch 24 having a central annular groove 25.

Slidably mounted in vertically spaced bearings 25^a outside the gear casing 19 is an upright rod 25^b, secured to which is a clutch controlling member 26 which projects into the groove 25.

Pivoted between its ends is a bell crank lever 27, having at one end an elongated slot 28 which receives a pin 29 on the outer end of the clutch controlling member 26.

Pivoted to the other end of the bell crank lever 27 is a socket 30 internally screw-threaded to receive one end or a link 31 which is screwed into said socket. On the link 31 adjacent to the socket 30 is a lock nut 32.

Mounted on the end of the wringer opposite the gear casing 19 is a bracket 33 having a substantially flat horizontal portion 33^a, 110

provided with an upwardly extending curved flange 34, provided with three notches 34^a, 34^b, and 34^c.

Above the portion 33^a of the bracket 33 is a plate or the like 36 which may have upwardly extending flanges at its side edges, and which is provided at its ends and at its middle portion along its side edges with opposite pairs of ears 36^a.

10 Mounted in an opening in the central part of the portion 33^a of the bracket 33 is an upright bolt 35, the upper end of which extends through the plate 36, as illustrated in Figure 5.

15 The lower end of the bolt 35 projects below the portion 33^a of the bracket 33 and has mounted thereon a nut 36^b. Between the nut 36^b and the lower surface of the portion 33^a is a coil spring 37, the tension of which 20 yieldingly holds the plate 36 snugly against the portion 33^a and the flange 34.

On the bottom of the plate 36 is a lug 38 arranged to coact with the notches 34^a, 34^b, and 34^c.

25 Mounted in the middle pair of ears 36^a is a pin or pintle 39 on which is pivoted one end of a controlling lever 40.

The controlling lever 40 is pivotally mounted on the pintle 39, so that it may be 30 swung to different positions to be supported on either end of the plate 36.

The lever 40 is illustrated in full lines in Figure 2 in one of such positions, and in dotted lines in said figure in another of 35 such positions. The lever is also shown in full and dotted lines in its different positions in Figure 4.

The end of the link 31 opposite the socket 30 is up-turned and extended through the 40 opening in the plate 36, as shown in Figures 4, 5, and 7, and may be held in position by means of a cotter pin 31^a.

In order to lock the wringer in various positions of its swinging movement, around 45 the shaft 18, I have provided a locking bolt 45, slidably mounted in bearings 45^a on the bracket 10. On the locking bolt 45 is a collar 45^b. Between the collar 45^b and one of the bars 45^a is a coil spring 45^c for normally 50 moving the locking bolt 45 toward its locking position.

Pivoted to the bolt 45 is a link 46 which is pivotally connected with a lever 47. The lever 47 is pivoted on the outer end of the 55 arm 10^a.

Inasmuch as my wringer is arranged to swing to different positions with relation to its support, it will be obvious that there are substantial advantages in arranging the 60 lever 40 so that it may be projected in different directions with relation to the wringer, as herein shown.

With power operated wringers it sometimes occurs that clothing or other articles 65 going through the wash will become wound

on the wringer rolls, and in order to save the clothing from being torn it is necessary to instantaneously stop the wringer.

Some mechanism for instantaneously stopping the wringer is also desirable in order to avoid injury to the operator whose hands might be drawn between the rolls. 70

There are various devices for permitting the instantaneous release of the tension on the wringer rolls, and one of my objects is to 75 provide such a device in this instance, but such a device does not solve the entire problem which is faced by the operator of a power operated wringer.

If the tension is instantly released, it will 80 be noted that the lower wringer roll may still be left in gear and it sometimes occurs that the rubber of the wringer rolls is torn out in chunks even after the tension has been released, when the lower wringer roll is 85 still left in gear with the power shaft.

I have, therefore designed the present device which is adapted not only to instantaneously release the pressure on the wringer rolls, but also to simultaneously and automatically throw the reverse gear into neutral 90 position.

It may be mentioned in this connection that when the lug 38 is in the notch 34^a, the link 31 will have been moved to position for 95 operating the bell crank lever 27 and the clutch controlling member 26, for throwing one member of the double clutch 24 into engagement with the coacting clutch member on the gear 20, for rotating the wringer rolls 100 in one direction.

When the lug 38 is in the notch 34^c, the parts will have been operated for bringing the double clutch member into coacting engagement with the clutch member on the gear 21, for rotating the wringer rolls in the 105 opposite direction.

When, however, the lug 38 is in the center notch 34^b the double clutch member 24 will 110 be held in neutral position.

In this connection it may be mentioned that the spring 37 yieldingly holds the lug 38 in whichever of the notches said lug may have entered, against any accidental displacement. 115

I will now describe my special mechanism for permitting instantaneous release of the tension on the wringer rolls for simultaneously and automatically throwing the reverse gear mechanism into neutral position 120 when the tension is released.

Mounted in the uprights 11 are strong coil springs 50 which are arranged in cooperative relation with the upper wringer, roll shaft. 125

Mounted horizontally between the upper ends of the uprights 11 is a cross bar 51 which has each of its ends detachably mounted in a socket member 62 which is secured adjacent to the outer face of each of 130

the members 11, the said sockets 62 being designed to receive a small portion of the ends of said bar 51, as clearly shown in section in Figure 1.

5 Mounted on top of the springs 50 and beneath the ends of the bar 51 are plates 51^b which are designed to extend downwardly and inwardly, and mounted on the upper edge of a cross bar 51^c. The plates 51^b and 10 the bar 51^c serve to hold the springs 50 in position when the tension is released therefrom.

Mounted in each end of the bar 51 is a thumb screw 53, said thumb screws being so 15 arranged that their lower ends rest on the upper face of the plates 51^b. The bar 51 is hinged at its central portion by means of a hinge 52, said hinge being secured to the under face of said bar. The upper face 20 of one of the members of said bar 51 is provided with a bracket 54 on which is mounted a pivoted hook bar 55, one end of which is provided with a hook 56 designed to engage an angular catch plate 57, said catch 25 plate being mounted on the top face of the opposite member from which the bracket 54 is mounted. A spring 58 is provided under the opposite edge of the lever 55 for the purpose of yieldingly holding the hook 56 30 into engagement with the plate 57, the said hook 56 and the plate 57 being designed to hold the members of the bar 51 in a rigid relation relative to each other, the thumb screws 53 being mounted in such a manner 35 that the upward yielding pressure of the springs 50 will have a tendency to break the bar 51 at its central portion, the breaking tendency being held by means of the hook 56.

40 Pivoted to each member of the bar 51 is a link 59. The links 59 are extended downwardly and across each other, as shown in Figure 1, and are slidably mounted on the link 31 at their lower ends.

45 On the link 31 are annular collars or the like 60 spaced from each other, and form limiting devices so located as to accomplish the purposes hereinafter more fully explained.

50 The outer ends of the bar 51, when said bar is in horizontal position, are received in sockets 62.

In the practical operation of my improved device, the bar 51 is moved to its 55 horizontal position, the catch devices are moved to coacting locking position, and the screws 53 are then screwed tending to impose tension on the springs 50.

Assume that the clutch device, forming 60 part of the reverse gear mechanism, is in position for throwing the proper-gears into operative relation for rotating the wringer rolls convergently in one direction, when the power shaft 18 is rotated, then if it is desired 65 to instantaneously release the tension

on the wringer rolls, the operator may strike downwardly on the handle end of the lever 55 against the pressure of the spring 58 for releasing the catch devices.

The upward pressure of the springs 50 70 against the members of the bar 51 will serve to throw the central portions of said bar upwardly and the parts will jump to the position shown in dotted lines in Figure 1.

The sockets 62 serve as fulcrums for the 75 outer ends of the bar 51 when the locking device at the center of the bar is released.

Assume that the link 31 has been moved toward the right, before the tension members are released, it will be seen that when 80 the bar 51 jumps upwardly, the momentum of the members of the bar 51 will be sufficient to cause one of the links 59 to engage the right-hand collar 60 and force the link 31 toward the left to its middle position 85 when the reverse gear mechanism will be moved to neutral position.

The movement of the link 31 would be toward the right, when the tension imposing devices are released, if the rod 31 were 90 at its left position of movement when the catch devices were released.

In any event the arrangement of the parts is such that whenever the catch devices are 95 released and the central portion of the bar 51 jumps upwardly, the link 31 will be quickly moved to position for throwing the reverse gear mechanism into neutral and disconnect the wringer from the power shaft. 100

I consider this an important feature of my invention, insomuch as I have found that where the tension on the wringer rolls is released, but the lower roll is not thrown out of gear, the rotation of the lower roll 105 with clothes wrapped on it will sometimes results in tearing chunks of rubber out of the wringer rolls.

Even if the tension is released, if clothing has been wrapped around the lower roll, 110 it will be seen that clothing might be torn by contact with the frame of the machine by the continued rotation of the lower wringer roll.

The mechanism whereby I have accomplished the desired objects of my device is 115 simple and inexpensive, and is accurate and certain in its operation.

The releasing device is easily operated and can be operated instantaneously in case 120 of any trouble.

Some changes may be made in the construction and arrangement of the parts of my improved device without departing 125 from the essential features and purposes of my invention, and it is my intention to cover by my claims any modified forms of structure or use of mechanical equivalents which may be reasonably included within their scope. 120

I claim as my invention:

1. The combination of a wringer having cooperating rolls, a power shaft, operating means driven by said power shaft for imparting a forward rotary movement to a given roll, operating means for imparting a reverse movement from said power shaft to said given roll, means for imposing tension on said rolls, adapted to be instantly released, and means actuated by the recoil of said tension device for throwing said forward and reverse operating means out of operation when said tension means is released.
2. The combination of a wringer having coacting rolls, a power shaft, means including a reverse gear mechanism for connecting the power shaft with said rolls and including a reversing clutch, means for imposing tension on said rolls, means for instantaneously releasing said tension means, and means for operatively connecting said tension imposing means with said reverse gear mechanism so that the said tension means will automatically move the clutch from either 25 of its operative positions to an inoperative

position when the releasing mechanism has been operated.

3. In a device of the class described; the combination of a wringer with a reverse gear mechanism; means for operating said reverse gear mechanism, and moving it to different operative positions, and to neutral position; said last means including a longitudinal movable link; springs for imposing tension on the wringer rolls; a centrally hinged sectional cross bar above said springs; adjustable screws in said cross bar for varying the tension on said spring; socket devices at the ends of said cross bar; coacting locking devices on the adjacent portions of the cross bar at the hinged ends thereof; one of said locking devices having a handle portion adapted to be actuated for instantaneously releasing the locking devices; spaced stop members on said link; and rods pivoted to the members of the cross bar and slidably mounted on said link on opposite sides of said stop members.

Des Moines, Iowa, May 21, 1919.

OLIVER B. WOODROW.
